ERNEST JAMES ROBERTS, OF CHRISTCHURCH, NEW ZEALAND.

FEED-GUIDE FOR LITHOGRAPHIC AND OTHER PRINTING MACHINES.

1,092,455.

Specification of Letters Patent.

Patented Apr. 7, 1914.

Application filed February 11, 1913. Serial No. 747,684.

To all whom it may concern:

Be it known that I, ERNEST JAMES ROBERTS, a subject of the King of Great Britain, residing at Christchurch, New Zealand, have 5 invented a new and useful Improved Feed-Guide for Lithographic and other Printing Machines; and I do hereby declare the following to be a full, clear, and exact description of the same.

10 This invention relates to the adjustable guides employed upon the feeding boards of lithographic and other printing machines for the purpose of guiding the sheets to be printed into the feeding rollers of the machine.

15 The invention has been designed in order to provide a construction of guide such as may be quickly and accurately adjusted in position to suit the varying widths of sheets 20 and which when so adjusted may be rigidly fixed from further movement.

25 The invention consists in forming the guide of two main parts, one being a bearing fixed rigidly to the feeding board and having a hollow spindle internally screw threaded 30 mounted to rotate therein, and the other a sliding frame mounted to slide across the feeding board and having a screw on its back which fits into the threaded spindle so that by the rotation of the spindle it may be moved in either direction, and having mounted on its front end a vertically adjustable foot and a block, spring cushioned to be kept in engagement with the feeding 35 board. The adjustable foot is adapted to have the sheet's edge passed beneath it so as to keep the sheet flat upon the board, while the block is used to engage with the sheet's edge and thereby aline it as required.

40 In fully describing the invention reference will be made to the accompanying drawings, in which:—

45 Figure 1 is a perspective view of the whole device in its assembled condition, Fig. 2 is a view of the bearing fixed upon the feed board. Fig. 3 is the regulating spindle. Fig. 4 is a view of the sliding member looking from the back thereof. Fig. 5 is a front elevation of such member. Fig. 6 is a back view of the adjustable foot for 50 mounting on the front of the sliding member. Fig. 7 is a front view of the guide block.

55 Referring to Figs. 1, 2 and 3, A is the fixed bearing made in any approved manner such as to provide for the mounting of the internally screw threaded spindle B

therein in such a way as to permit of the spindle's rotation but to prevent any longitudinal movement thereof. At its outer end the spindle is provided with a hand wheel or 60 index wheel C by means of which it may be rotated.

Fitted over the top of the bearing A is the sliding device shown in Figs. 4 and 5 and consisting of a top plate D that slides over 65 the top of the bearing and a front plate E extending down in front of such bearing and the side wings F overlapping the sides of the bearing. These side wings are formed with the longitudinal slots f therein, which slots 70 fit over pins or studs a projecting from the sides of the bearing and thus serve to guide the sliding device and prevent it from any loose movement as it moves to and fro across the bearing. A long screw G projects from 75 the back of the front plate E and is screwed into the end of the spindle B and thus by the rotation of this spindle, the sliding device may be moved in or out to any desired point. The means for locking it at any point are 80 shown in Figs. 1 and 2 and consist of a wedge shaped block H mounted on a screw H' projecting upward from the top of the bearing A and passing through a slot d (Fig. 4) in the top plate D of the sliding 85 device. A thumb nut h is screwed on to this screw and serves to force the block H down to engage with the slot and thus lock the sliding device rigidly to the bearing.

Upon the front face of the plate E of the 90 sliding device is mounted the vertically adjustable foot shown in Figs. 1 and 6. This foot is shaped, as shown, with a pair of flanges J extending outwardly from the bottom end of an upright portion J' that is 95 formed with slides j that fit into guides e (Fig. 5) upon the plate E. This foot is provided with a screw K that passes up through the top plate D of the sliding device and a nut K' is screwed on its top end so that by 100 its manipulation the foot may be raised or lowered. The flanges J overlie the feeding board of the machine and by the adjustment of the foot their distance from the surface of the table may be regulated. A flat 105 spring k is placed in between the top of the upright J' and the top plate D of the sliding device in order thus to prevent any looseness in the positioning of the foot.

The bottom of the upright J' is cut away 110 as shown in Fig. 6 and the edges of the cut away portion are recessed as at M to receive

the block N (Figs. 1 and 7) which is passed through from the back of the upright and is provided with the flanges N' fitting into the recesses M. These flanges thus lie between the upright J' and the face of the plate E and a spring O is placed in compression between the top of the block and the top of the recess in the upright J' so as to cause the block to fit hard down on to the feed board of the machine. A flat spring P is also placed between the block and the plate E which serves as a friction spring to hold the block from movement as the foot is being raised or lowered. Thus in the manipulation of the device the block N will engage the edge of a sheet placed on the feed board and the edge of which is passed beneath the flanges of the foot. These flanges will at the same time keep the sheet flat upon the board and by reason of their adjustability may be regulated to suit varying thicknesses. The position of the block may be adjusted by moving the sliding member across the bearing A by the rotation of the spindle B in the manner already described. The block N is kept steady by means of the nose R upon the foot fitting into the groove n on the front face of the block.

If desired the bearing A may be provided with gage markings S (Fig. 2) on its surface and the top plate D of the sliding member provided with transparent plates S' (Fig. 4) which will exhibit the gage markings S through them and permit of a fixed line on such plates being caused to coincide with anyone of such gage markings as may be desired, thereby allowing for the adjustment of the guide. If desired also the wedge block H may be made to project at its inner end as an index finger adjacent to the hand wheel C of the actuating spindle B, which wheel is then divided on its edge

with divisional markings. This will permit of the adjustment of the guide by the rotation of the spindle. 45

What I do claim as my invention and desire to secure by Letters Patent is:—

1. In means for the purpose herein described a bearing fixed upon the feed board, an internally threaded hollow spindle mounted to rotate in such bearing, a sliding member adapted to move over the bearing and having a screw fixed thereto and screwing into the hollow spindle, a foot plate carried on the front of the sliding member and adjustable vertically thereon, a guide block mounted on the front of such member, gage plates upon the fixed bearing and transparent plates upon the sliding member extending over such gage plates, substantially as specified. 50

2. In means for the purpose herein described a bearing fixed upon the feed board, an internally threaded hollow spindle 65 mounted to rotate in such bearing, a sliding member adapted to move over the bearing and having a screw fixed thereto and screwing into the hollow spindle, a foot plate carried on the front of the sliding member and adjustable vertically thereon, a recess in the foot plate a guide block inserted in such recess, a spring arranged between the top of the guide block and the top of the recess in the foot plate and a spring plate arranged 70 between the back of the guide block and the front face of the sliding member, substantially as specified. 75

In testimony whereof, I have signed this specification in the presence of two subscribing witnesses. 80

ERNEST JAMES ROBERTS.
